UNITED STATES PATENT OFFICE.

GEORGE ALDERSON, OF LA SALLE, ILLINOIS.

TANK HEATER.

Application filed October 20, 1921. Serial No. 509,143.

To all whom it may concern:

Be it known that I, GEORGE ALDERSON, a citizen of the United States, residing at La Salle, in the county of La Salle and State 5 of Illinois, have invented certain new and useful Improvements in Tank Heaters, of which the following is a specification.

This invention relates to tank heaters adapted for use in connection with live stock 10 watering tanks for the purpose of heating the water in cold weather so as to prevent the same from freezing. The heater is adapted to be partially submerged in the water tank, and is adapted to burn coal, 15 wood, cobs or other fuel for generating the requisite heat. In tank heaters heretofore constructed, with which I am familiar, the products of combustion are delivered more or less directly from the fire box to the outlet stack and always at a considerable distance from the bottom of the tank, with the result that the water in the lower portion of the tank is not heated and the efficiency of the heaters is relatively low.

One of the primary purposes of my present invention is to provide a tank heater which will conduct the products of combustion from the fire box along the bottom of the heater casing in proximity to the bottom of the tank, so that this water in the bottom of the tank will be heated, and because of the long path of travel of the hot products of combustion from the fire box, a high efficiency in the operation of my improved heater will result.

Another feature of my invention resides in the provision of a removable perforated member which may be positioned in the fire box above the grate so as to shut off a portion of the grate when coal is to be used as fuel, thereby reducing the rapidity of combustion and also serving to feed the fuel onto that portion of the grate where it should be burned. The member is removable, as previously stated, so that the full capacity of the grate may be utilized when required, such for instance, as when burning cobs or other like fuel.

A further feature of my invention resides in the provision of a shutter plate which is so mounted that it may be removed when the heater is initially started up, thus permitting a direct draft from the fire box to the outlet stack, and when the fire has been well started, this shutter plate may be inter-

posed between the fire box and the outlet stack to shut off direct communication and compel the products of combustion to travel in a circuitous path through a delivery flue downwardly along one side of the casing, 60 thence transversely across the casing beneath the fire box, and thence upwardly along the opposite wall of the casing to the outlet stack. This path of the products of combustion results in thoroughly heating 65 the bottom of the heater casing, as well as the vertical walls and renders the heater extremely efficient.

Other objects and many of the inherent advantages of my invention will be readily 70 appreciated as the same becomes better understood by reference to the following description, when considered in connection with the accompanying drawings:

Referring to the drawings—

Fig. 1 is a vertical sectional view through a heater embodying my invention;

Fig. 2 is a transverse sectional view on the line 2—2 of Fig. 1; and

Fig. 3 is a plan view with the top or cover 80 of the heater removed to show the underlying parts.

From an inspection of the drawings, it will be apparent that my improved heater comprises essentially a casing 4, shaped substantially as shown in the drawings and constructed in any suitable manner. The casing may, if desired, be made of sheet-metal, but preferably it is constructed of cast iron made in two parts equipped with abutting flanges 90

5 and 6 securely connected together by bolts 7. These casing sections are equipped on their inner faces with inwardly projecting ribs or studs arranged to hold the interior parts in position. As shown, lugs 8, 9 and 11 are provided upon which the fire grates 12 and 13 rest. Inwardly disposed ribs 14 beneath the grates serve as supports for the bottom portions 15 and 16 of the flue walls 17 and 18 which are also held in position by 100 lugs 19 and 21. The flue wall 18 serves as one end wall of the fire box 22, the other end wall 23 being supported upon the lugs 8 and spaced from the wall 17 so as to provide an air inlet flue 24 communicating at one end 105 with the atmosphere at the top of the heater, and at its other end beneath the grates so as to supply air through the grates to the fire box.

It will be observed that the air supply flue 110

24 is of less width than the casing, leaving spaces 25 at each side thereof through which communication is established between the fire box 22 and the flue 26 at one end of the casing. This flue extends downwardly, then transversely, as indicated at 27, along the bottom of the casing beneath the fire box, and then upwardly, as indicated at 28, along the opposite end wall where it communicates 10 at its delivery end with an outlet stack 29 of any desired height, and preferably equipped with a damper 31 of usual construction. It will be apparent therefore that the products of combustion from the fire box pass through 15 the openings 25 thence through sections 26, 27 and 28 to the stack 29 where they are delivered from the heater.

When burning cobs, wood or other light fuel, it is usually desirable to utilize the 20 full surface of the grates 12 and 13, but when burning coal, coke or the like only substantially one-half of the grate surface is required. I have therefore provided a member 32, preferably curved-shaped, supported at 25 its lower end in suitable bearings 33 formed on the inner face of the casing, and disposed in inclined position so as to shut off or cover the grate 12 and at the same time direct the coal onto the grate 13 where it is burned. 30 To facilitate the combustion of the fuel, this member 32 is equipped with air openings 34, and near its lower edge it is slotted, as indicated at 35, so that air, in addition to that passing upwardly through the grate 13, may 35 enter the fire box to support combustion.

It will be observed from Fig. 1 that the upper portion of the flue section 28 is normally separated from the fire box by a shutter plate 36 supported in inclined position 40 with its lower edge 37 resting in supporting brackets 38 formed on the wall 18. Near its upper end the plate is equipped with trunnions 39 which are seated in bearings 41 formed in the top of the casing. The upper 45 projecting portion 42 of the shutter plate forms a handle by which the plate may be manipulated. When it is desired to establish direct communication between the fire box and the outlet stack 29, the plate may be 50 lifted to disengage it from the brackets 38 permitting it to hang suspended from the fire box, but since in this position it is subjected to excessive heat, I prefer to remove the plate entirely from the casing when not 55 positioned as shown in Fig. 1, and with this end in view the bearing members 41 are separated by a slot 43 extending transversely between the bearings and of sufficient width to permit the withdrawal and insertion of the 60 plate 36 therethrough. The casing is closed at its upper end by a cover plate 44, and when the shutter plate is to be removed or replaced this cover is lifted off. The shutter plate is then lifted to free the trunnions from 65 their bearings whereupon it is turned

thru an angle of 90° in alinement with the slot 43 so that it can be slid to the left viewing Fig. 1, sufficiently to free it from the bearings and permit it to be lifted out through the opening above the fire box. 70 For the purpose of regulating the supply of air to the fire box, the cover plate 44 is equipped with slideable shutter 45 adapted to wholly or partially close the upper end of the air inlet flue 24. This shutter may be 75 adjusted to any desired position in the slide-ways 46 formed on the upper face of the cover 44.

In the operation of my improved heater, the fire box is charged with fuel, the member 80 32 being removed or left in, depending upon the character of the fuel employed. When the fuel is initially ignited, the shutter plate 36 is preferably removed for a limited period, permitting direct draft from the fire 85 box to the stack 29 until the fuel is well ignited whereupon the shutter plate 36 is replaced in the position shown in Fig. 1, thereby shutting off the direct communication between the fire box and the stack. 90

The products of combustion are now compelled to travel through the openings 25 into the flue 26, downwardly in this flue to the bottom of the casing, then along the bottom through the flue 27 and then upwardly 95 through the flue 28 to the stack. This circuitous path of the products of combustion causes the end walls and also the bottom wall of the casing to be thoroughly heated, thus heating the surrounding water in the 100 lower portion of the tank and removing a maximum quantity of heat units from the products of combustion before they are delivered from the stack with the result that the heater possesses a high degree of efficiency. When ash removal is required, one 105 of the grates, or both, if the fire is not burning, may be lifted out, whereupon the ashes may be removed with a suitable implement through the top, the cover 41 having been 110 first taken off.

It is believed that my invention, its construction, mode of operation, and many of its advantages will be understood from the foregoing without further description, and 115 while I have shown and described a preferred embodiment, obviously the details of construction may be varied within considerable limits without departure from the essence of the invention as defined in the 120 following claims.

I claim:

1. A tank heater, comprising a casing, a fire box therein, a grate forming the bottom of said fire box, an air inlet flue for 125 supplying air beneath said grate, and a delivery flue communicating with one side of said fire box above the grate, and extending downwardly around said air inlet flue and along one wall of said casing, then horizon- 130

tally across the bottom thereof beneath the fire box, and thence upwardly along the opposite side of the casing.

2. A tank heater, comprising a casing, a fire box arranged therein, a grate forming the bottom of said fire box, a removable perforated inclined member adapted to be disposed over a portion of said grate, and means for conducting the products of combustion transversely across said casing beneath said grate.

3. A tank heater, comprising a casing, a fire box arranged therein, a grate formed in the bottom of said fire box, a curved perforated member disposed in inclined position in said fire box over a portion of said grate, means for supplying air beneath said grate, a delivery stack located adjacent one side of said casing, a flue communicating with one side of said fire box and extending downwardly, thence laterally across the casing beneath the grate, and thence upwardly into communication with said stack, and a shutter plate interposed between said stack and said fire box and normally forming one side of a portion of said flue, said plate being movable so as to establish direct communication between said fire box and said stack.

4. In a tank heater, the combination of a casing provided at the top adjacent one side with an air intake flue and adjacent the opposite side with a delivery stack, a fire box arranged within said casing, a flue extending from said fire box to said stack, a shutter plate extending the full width of the fire box and forming a portion of one of the walls of said flue, said plate having a narrow upper end, and means including slotted bearings for removably supporting said

shutter plate so that the same may be removed from the casing permitting the products of combustion from said fire box to directly enter said stack without passing through said flue.

5. In a tank heater, the combination of a casing, a fire box arranged therein, an outlet stack, a shutter plate comprising a wide lower portion and a narrow upper portion, means for supporting said shutter plate with the wide portion in position between said fire box and said stack, said means being slotted to permit removal of said plate from the casing upon lifting said plate and turning the same through a partial rotation.

6. In a tank heater, the combination of a casing, comprising complemental halves bolted together, a fire box arranged within said casing, a down flue at one side of the fire box, a cross flue beneath the fire box, an up flue at the opposite side of the fire box, and an air inlet flue extending downwardly through said down flue for supplying air to said fire box.

7. In a tank heater, the combination of a casing, a fire box arranged therein, a grate forming the bottom of said fire box, means for dividing the fire box so as to permit the feeding of fuel to a portion only of said grate, an air supply flue extending from the top of said casing to a point beneath said grate, and means for delivering the products of combustion from said fire box, comprising a flue surrounding said air inlet flue and communicating with the fire box, a cross flue beneath the fire box, and an up flue at the opposite side of the fire box.

GEORGE ALDERSON.
